ERNEST G. UNGER, OF BROOKLYN, NEW YORK, ASSIGNOR TO HALLIWELL-SHELTON ELECTRIC CORPORATION, OF NEW YORK, N. Y., A CORPORATION OF NEW YORK

COMBINED SPINDLE AND CROQUIGNOLE HAIR WAVING HEATER

Application filed October 31, 1929. Serial No. 403,899.

The invention relates in general to a combination heater for use in waving hair on a person's head in practicing both the croquignole and spindle methods of waving.

5 It is the present practice in the hair waving art to provide two different types of heaters for use in such methods, one constituting a two-jaw spring gripping type designed to clamp the hair under treatment 10 lengthwise between the jaws, and the other constituting a hollow tubular type for encircling a coil of hair when wound spirally on a spindle and for this reason identified as a spindle method.

15 The primary object of the invention is to eliminate the necessity of the operator using two forms of the heaters in the hair waving work, and to provide a single article of manufacture comprising a basic unit which 20 may be used alone in practicing one method by the insertion in place of another unit constituting an attachment which may be used in practicing the other method and in this way a single article may be used selectively for practicing either method of waving.

Broadly, this object of the invention is attained by using a croquignole type of heater as the basic unit and utilizing the jaw 30 clutch spring in such heaters for the purpose of clamping between the jaws an additional plate which will coat with the jaws to form a cylindrical or other tubular form of heater for use in the spindle method.

35 In some methods of hair waving by means of the spindle method there is required a heating tube of greater length than is usually required in the croquignole method, and accordingly the present disclosure features 40 the providing of a tube forming part of the attachment which will coat with the croquignole heater forming jaws to provide an extension or elongation thereof and thus provide a tubular heater of any requisite 45 length.

It is a usual practice to support hair waving heaters from the electric leads which supply current to the heater element contained within the shells which outline heaters of this character. In using croquignole

heaters, it is the usual practice to group the heaters about the head of the person under treatment with the heaters extending more or less horizontally and with their long sides in engagement with or tangent to the head. 55 In using the tubular heaters in the spindle method, the tubes extend more or less perpendicularly to the head with one end adjacent the scalp, or differently expressed, the axis of the heaters extends somewhat radially of the head and of course at varying angles to the vertically extending electric leads which supply the heaters. In order to provide for this variation in angular adjustment between the supporting electric leads 60 and the combination heater herein featured, the invention features the use of heater positioning means between each of the supporting electric leads and the basic unit or that part of the construction which is common to 65 both forms of heaters. These positioning means are designed to permit an easily manipulated, quick adjustment to the same with relation to both the suspending leads and the part of the device carried thereby so as 70 to suspend the heaters in that angular position required for the most efficient practicing 75 of the different methods.

Various other objects and advantages of the invention will be in part obvious from an 80 inspection of the accompanying drawing and in part will be more fully set forth in the following particular description of one form of mechanism embodying the invention, and the invention also consists in certain new and 85 novel features of construction and combination of parts hereinafter set forth and claimed.

In the accompanying drawing there is 90 shown in full lines in Fig. 1 a view in side elevation of a preferred embodiment of the invention with both the basic and attachment units assembled to form a cylindrical spindle winder type of heater and showing in dotted 95 outline the heater shifted relative to the supporting electric lead to dispose the heater in the position which it would be used when acting on a coil of hair adjacent the top of the head and heating the same by the spindle method. 100

Fig. 2 is a view in end elevation of the device as shown in Fig. 1 looking at the same from the left hand side of such figure and showing a portion of one of the handles broken away to disclose the manner of securing the heater positioning means to the heater;

Fig. 3 is a view in side elevation of the attachment unit or filler shown at the lower portion of the two preceding figures and removed from the basic unit constituting the croquignole heater;

Fig. 4 is a view mainly in end elevation and partly in vertical transverse section taken on the line 4—4 of Fig. 3 looking in the direction indicated by the arrows, and

Fig. 5 is a perspective view of the attachment unit shown in Figs. 3 and 4.

Referring first to the showing in Figs. 1 and 2, it will be understood that the heater comprises essentially three long curved portions 10, 11 and 12 with their inner concaved sides 13 facing each other and coacting as shown particularly in Fig. 2 to form a cylindrical heater 14. The heater thus formed is provided with a slot 15 between the two members or jaws 10 and 11 but otherwise corresponding to conventional forms of hair waving heaters of the cylindrical type now in general use.

Considering first the cylinder forming members or jaws 10 and 11, it is a feature of this disclosure that they are pivotally connected to constitute a heater of the type commonly used in practicing the croquignole method of hair waving. In the instant case, each of the jaws 10 and 11 is provided with a laterally extending handle mounting plate 16, welded to the outer face of the jaws 10 and 11. To the outer face of each of these plates is fastened a block of insulating material and which two blocks constituting a pair of handles 17 and 18 extending parallel to each other and secured by fastening means 19 to their respective plates 16. The handles 17 and 18 are disposed in parallelism for actuating the jaws 10 and 11 somewhat following conventional practices in this respect. The jaws 10 and 11 are pivotally mounted to each other by means of a pivot bolt 20 passed through opposed pairs of lugs 21 and 22 each pair extending in mutually overlapped relation from the opposite edges of the plates 16. A spring 23 is coiled about bolt 20 and has its opposite ends 24 in bearing engagement with the inner faces of the plates 16 adjacent their outer ends and acting thereon in a tendency to move the jaws 10 and 11 towards their closed clamping position.

The jaws 10 and 11 are provided with heating units contained therein and these heating units are supplied with electric current through wires 25 contained in heater supporting leads 26 usually depending from

overhead brackets and other forms of supports.

As shown in Fig. 2, the inner face of one of the handles 17 is recessed adjacent its outer end to provide a slot 27 and positioned in this slot is one end of an L-shaped metal pressing 28 constituting a heater positioning means. The portions within the slot 27 are enlarged as shown in dotted lines in Fig. 1 and the enlarged end is provided with an eye 29. A pivot pin or rivet 30 is passed through the eye 29 and through the handle 17 as more particularly shown in Fig. 2 for the purpose of pivotally connecting the means 28 to the handle and for securing the means in frictional tight engagement with the handle. In this way the handle and the positioning means 28 will be maintained automatically in whatever angular position they may be shifted as suggested in the full and dotted line showings in Fig. 1.

The outer end of the pressing 28 is bent at right angles to the part pivoted to the handle as shown in Fig. 2 to extend above and across the space formed between these two handles 17 and 18. This overlapping portion 32 is provided with a ring 33 through the eye of which extends the leads 26 and this eye is so designed that the leads fit therein more or less snugly so as to provide a frictional resistance to any tendency of the lead to shift freely through the eye.

The free edges 34 and 35 of the jaws 10 and 11 are rounded as indicated in Fig. 2 so as to present a smooth, rounded edge to the clamping jaw heater when used in the croquignole method.

The attachment herein featured and particularly shown in Figs. 3 to 6 comprises essentially a long plate 36 having a length corresponding to the length of the jaws 10 and 11, curved transversely of its length as indicated in Fig. 4, and having its longitudinal and end edges flanged to provide longitudinal strengthening flanges 37 and 38 and an end flange 39. Adjacent the end flange 39, the plate 36 is provided with a transversely extending curved clip 40, the ends of which project laterally beyond the plate 36 and engage the inner faces 13 of the jaws 10 and 11 to constitute as indicated in Fig. 2 means for limiting the closing movement of the jaws 10 and 11. It is appreciated also that clip 40 acts to prevent any outward or falling movement of the outer or left end of the attachment shown in Fig. 3 away from the jaws 10 and 11.

At the opposite or right hand end of plate 36, as viewed in Figs. 1, 3, and 6, there is provided a tubular extension 41 designed to form a prolongation of the tube formed by the parts 10, 11 and 12 as shown to the left of Fig. 1. The extension 41 includes a tubular part 42 of relatively small diameter and terminating at its outer end in a frusto-coni-

cal nose 43. The inner end of the extension 41 is enlarged over the diameter of the part 42 to provide a sleeve 44 having an internal diameter sufficient to telescope the adjacent 5 end of the jaws 10 and 11 when held in their open position by the plate 36 interposed therebetween. The attachment 41 is secured to the plate 36 by means of rivets 45 passed through spacing blocks 46 fitted between the 10 sleeve and plate shown in Fig. 4.

In operation and assuming for instance 15 that it is desired to use the device in practicing the method of waving hair by the croquignole method, the attachment is withdrawn from its engagement with the jaws 10 and 11 if the attachment happens to be in place. This is attained by pressing the handles together against the action of the spring 20 23 to an extent sufficient to release the clutching effect of the jaws on the attachment. The attachment is then slipped out of position by moving the same longitudinally to the right from the position shown in full lines in Fig. 1. The attachment can then be laid aside and 25 the remaining part used conventionally as is usual in the use of croquignole hair waving heaters. During this use, the heater positioning means 28 is shifted into the vertically extending position forming a prolongation 30 of the length of the handle as shown in Fig. 1, if not already in this position.

Should it be desired to use the device in 35 the method of waving hair by the spindle process, the handles are pressed slightly together so as to open the jaws a distance sufficient to permit the insertion of the plate 36 between the rounded jaw edges 34 and 35 and shifted lengthwise until the jaws are seated within the sleeve 41. Releasing tension 40 on the handles will permit the spring 23 to exert a clamping action on the plate 36 and thus act to hold the attachment in place and form the cylindrical type of heater 45 commonly used in practicing this method of hair waving.

As noted before, the heaters are grouped 50 about the head in endwise engagement with the scalp and this necessitates an adjustment of each heater relative to its supporting lead to some set angle depending upon the position 55 of the heater on the head. When using the device as indicated in Fig. 1, it is the practice to first locate the heater in its proper position on the head and then by grasping the positioning means 28 it is possible to shift the same into the proper angle to permit the lead to fall vertically from its ceiling bracket or other supporting means. The heater is thus 60 located in position to eliminate or at least to minimize any pull on the hair under treatment.

By means of a device of the character described, it is possible to provide one form of heater which can be used selectively in practicing 65 different processes of hair waving and

in the practicing of which processes two radically different forms of heaters are required and in which each form of heater necessitates a positioning on the head different from that required by the use of the other heater. 70 The device disclosed can be quickly changed from one form of heater to another without necessity of using any tools or readjustment of parts and the change from one form to another simply involves the sliding of an extra unit or attachment into position or the withdrawal of this unit from position on the basic unit. The electric heating units are contained in the part common to both forms of heaters so that there is no necessity 75 of making or breaking an electric connection in changing from one form to the other. In those cases where different lengths of tubular heaters are required, it is simply necessary to provide attaching unit with different 80 lengths of tubular extensions. It is obviously possible in case a tubular heater opened at opposite ends is desired to either omit extension 41 entirely from the attachment or to substitute therefor the nose 43 alone, or 85 a plate or some other closure of the types now found on hair waving heaters of the tubular type. It is also possible to supply under the basic unit a set of attachments, each differing from the other in the character of 90 tubular or other extensions provided.

I claim:

1. In a device of the class described, the combination of three curved elements adapted to be assembled to form a hollow cylinder, and each forming substantially one third of the cylinder, two of said elements being pivotally connected to form a two jaw clamp for securing the other element between the edges of the clamp, and said two elements provided with electric heating means, said other element provided with a clip for engaging the inner faces of the jaw forming elements, and a tubular extension secured to said other element, said extension provided with a frusto-conical nose at one end and a sleeve at the other end for telescoping over the adjacent ends of the two jaw-forming elements to form a long cylinder open at one end and provided with a frusto-conical nose 110 at the other end.

2. In a device of the class described, the combination of three curved elements adapted to be assembled to form a hollow cylinder, and each forming substantially one third of the cylinder, two of said elements being pivotally connected to form a two jaw clamp for securing the other element between the edges of the clamp, and said two elements provided with electric heating means, said other element provided with a clip for engaging the inner faces of the jaw forming elements.

3. In an electric heater for use in waving hair, the combination with a heater for use 130

- in croquignole waving comprising a pair of jaws, each consisting of a long portion, curved transversely with the concaved sides facing each other, means for pivotally connecting each other, means for pivotally connecting said jaws, and handles secured to the jaws for moving the same into an open position, of an attachment therefor constituting a filler curved transversely and adapted to be inserted between a pair of opposing edges of the jaws to maintain them in open position and coacting therewith to form a hollow cylinder adapted for use in a spindle wave, a tubular extension secured to one end of the filler and adapted to constitute an extension of the cylinder formed by the jaws and filler, and springs acting on the jaws for clamping the filler in place.
4. In an electric heater for use in waving hair, the combination with a heater for use in croquignole waving comprising a pair of jaws, each consisting of a long portion, curved transversely with the concaved sides facing each other, means for pivotally connecting said jaws, and handles secured to the jaws for moving the same into an open position, of an attachment therefor constituting a filler curved transversely and adapted to be inserted between a pair of opposing edges of the jaws to maintain them in open position and coacting therewith to form a hollow cylinder adapted for use in a spindle wave, and springs acting on the jaws for clamping the filler in place.
5. A heater for use in waving hair by either the croquignole or spindle methods comprising three long transversely curved major elements disposed edge to edge and coacting to form a hollow cylinder, two of said elements hingedly connected to form a clamp, provided with heating means and constituting in the absence of the third element a complete heater for use in practicing the croquignole method of hair waving, and adapted to coact with the third element positioned between the same to form a tubular heater for use in practicing the spindle method of waving and means for securing said third element in cylinder forming position between the other two elements.
6. A heater for use in waving hair by two methods, comprising three long, major elements coacting to form a hollow tube, two of said elements hingedly connected to form a clamp, provided with heating means and constituting in the absence of the third element a complete heater for use in practicing one of said methods, the other element constituting a filler adapted to be disposed between and coacting with the said two elements to form a tubular heater for use in practicing the other method, and means for securing said third element clamped in position between the other two hingedly connected clamp forming elements.
7. In an electric heater for use in waving hair, the combination of three long portions, each curved transversely and adapted to be assembled in circumferential alignment to form a hollow cylinder, two of said portions constituting a pair of jaws for clamping the third portion in place therebetween, said jaws provided with handles extending in parallel relation, springs acting thereon and tending to move the jaws towards each other and the said two jaws provided with heating means.
8. An electric heater for use in waving hair, comprising a pair of spring pressed hingedly connected jaws and constituting a heater for use as a croquignole waver, and a filler fashioned to fit between the edges of the jaws on the side thereof remote from their hinge connection and clamped in position thereby to form a hollow heater for use as a spindle waver.
9. An electric heater for use in waving hair by both the croquignole and spindle methods comprising three curved elements coacting to form a cylindrical type of heater for use in practicing the spindle method, two of said elements constituting in the absence of the third element a two jaw clamping type of heater for use in practicing the croquignole method, one of said two elements containing a heating means and provided with a handle of insulating material, an electric lead for supplying said heating means and for supporting the heater as a whole, heater positioning means pivotally mounted at one end to the handle and in frictional engagement therewith and provided at the other end with an eye through which the electric lead is threaded, said frictional pivotal securing of the positioning means to the handle providing a means for positioning the heater when in either form at different angles to the supporting electric lead.
10. An electric heater for use in waving hair including a heater element, a handle projecting laterally therefrom, a heater positioning means including an L-shaped member provided with eyes at opposite ends, a pivot pin passed through one of the eyes and acting to secure said means in frictional and pivotal engagement with the handle, and an electric lead for supplying the heater, said lead threaded through the other eye and acting thereon to support the heater as a whole in different angularly adjusted positions.
11. In a device of the class described, the combination of an electric heater for use in waving hair and comprising a unit complete per se constituting a heater of the jaw clamping type and a unit constituting an attachment to the first named unit and adapted to coact therewith to form a heater of the tubular type, an electric lead for supplying said heater and for supporting the same when in the form constituting either type and a heater positioning device pivotally mounted at one

end on the heater and having its other end provided with means coacting with the lead for securing the two-jaw type of heater at a set angle to the lead and for securing the 5 tubular type heater at will at a different angle to the lead when rotated relative to said device.

12. An attachment for use in a hair waving heater, comprising a long plate curved transversely, a tubular member secured to one end 10 of the plate, and comprising a frusto-conical nose at its outer end and a sleeve at its inner end.

13. An attachment for use in a hair waving 15 heater, comprising a long plate curved transversely, a tubular member secured to one end of the plate, and comprising a frusto-conical nose at its outer end and a sleeve at its inner end, and a supporting foot at the other 20 end of the plate.

14. An attachment for use in a hair waving heater, comprising a long plate curved transversely, a tubular member secured to one 25 end of the plate, and comprising a frusto-conical nose at its outer end and a sleeve at its inner end, and a clip extending transversely of the plate and projecting beyond the edges adjacent the other end.

Signed at New York in the county of New 30 York and State of New York this 5th day of October, A. D. 1929.
